UNITED STATES PATENT OFFICE

ARTHUR A. G. LAND, OF CHICAGO, ILLINOIS

CHAIN-LINK WIRE FABRIC

Application filed December 7, 1928. Serial No. 324,464.

My invention relates to interwoven wire fabrics of the so-called chain-link type, and in one of its general objects aims to provide inexpensive, easily manufactured and unitary wire fabrics of this type in which different portions of the fabric have different sizes of mesh openings. Furthermore, my invention aims to provide main wire strands adapted to be interwoven by a relative spiral 5 advancing movement and designed to afford portions of a chain-link type of wire fabric in which parts of consecutively disposed main strands interweave directly to form relatively large meshes, and aims to provide 10 secondary wire strands of the chain-link type designed for cooperating with other parts of the main strands in forming the smaller meshes.

Moreover, my invention aims to provide interwoven wire fabrics of the chain-link type affording different sizes of openings in different longitudinal rows of meshes, and aims to accomplish this while employing wire strands, some of which strands extend for the 25 entire width of the fabric.

In employing wire fabrics for many purposes, it is desirable to have the meshes in one part of the fabric smaller than those in another part of the fabric, and with the so-called chain-link type of fabrics this could heretofore be accomplished only by connecting a plurality of separately manufactured wire fabrics having meshes of the desired different sizes.

35 For example, in a wire fence around a poultry yard, a relatively small size of mesh is needed for the lower portion of the fence to prevent the poultry from getting out of the yard, while a considerably larger mesh would 40 be ample for the higher portion of the fence which serves to keep out boys and other trespassers.

Since ordinary chain-link wire strands will only afford a uniform size of mesh, it has 45 been necessary for poultry fencing either to use a fence having needlessly small meshes in its upper and major portion (and hence involving a needlessly high cost owing to the large amount of wire required for it and owing also to the cost of interweaving a need-

lessly large number of long strands), or to make the fence of differently meshed wire fabrics which are secured to each other during the erection of the fence. Since the ordinary user of such a fence does not make 55 either a secure or a neat job of thus interconnecting two fence portions, the resulting fence is apt to be both insecure and unsightly, besides requiring considerable additional labor for connecting the two wire mesh portions of the fence.

Similar situations arise with wire fabrics needed for many other purposes. For example, the mesh needed for the upper portions of a wire fence around the yard of a 65 factory, or around a garden, could be much larger than the meshes required for the lower portions of the same fence. Indeed, a saving of about twenty percent in the cost of the needed wire could be made if a single fabric 70 affording these different sizes of meshes could be obtained.

My present invention aims to provide relatively simple, easily manufactured and economical wire fabrics for such purposes. It 75 also aims to provide a wire fabric construction which readily permits portions of the fabric to have meshes differing in size from the meshes in other portions of the fabric, thereby producing ornamental effects which heretofore could not be obtained with chain-link wire fabrics. Furthermore, my invention aims to provide a construction for chain-link fabrics which will permit of wide variations in the size of the meshes in different parts of 80 the fabrics, and which will permit meshes of different sizes to be employed in variously disposed parts of the fabric.

Generally speaking, I accomplish the objects of my invention by making fabrics composed either mainly or entirely of main and secondary zigzag strands all of which may be flattened spirals in their general form with the main strands corresponding in length to the width of the proposed fabric, while the 85 secondary strands are shorter and correspond in their lengths to the width of the proposed small-meshed part of the fabric. Each secondary strand has its zigzag formations of uniform length and spread, and each main 90

strand has minor zigzag formations of similar spread and length extending for a part of the main strand which corresponds approximately in length to that of one of the secondary strands, so that these parts of the main strands can have the secondary strands interposed between them. Each main strand also has another part (and for many fabrics its entire remaining part) preformed into major zigzag formations which interweave in the consecutive main strands, each of these formations having a spread which has a definite arithmetical relation to the spread of one of its said minor zigzag formations.

Illustrative of embodiments of my invention, Fig. 1 is an elevation of a fragment of a fabric in which two secondary strands are disposed between the minor zigzagged portions of two consecutive main strands, each of these two secondary strands being interwoven with the other secondary strand and also with the minor zigzagged portion of one main strand, the meshes being all of uniform height.

Fig. 2 shows a fragment of a fabric in which two secondary strands are also disposed between the minor zigzagged portions of every two consecutive main strands, but in which the meshes in the minor portions are of less height than those in the major portions.

Fig. 3 and Fig. 4 are fragmentary elevations of two fabrics in which the secondary strands interposed between the minor zigzagged portions of two consecutive main strands vary in number in different parts of the small-meshed section of the fabric, and in which the main strands do not interweave with each other in this small-meshed section of the fabric.

Fig. 5 shows a fragment of a wire fabric similar to that of Fig. 4, but with certain secondary strands terminating at a greater distance from the major zigzagged portions of the main strands than in Fig. 4.

Fig. 6 shows a fragment of a wire fabric of similar construction to that of Fig. 1, but in which the major strands have a portion of major zigzag formation interposed between two portions of minor zigzag formation.

Fig. 7 is a fragmentary elevation of a wire fabric in which non-consecutive pairs of main strands are continued beyond their major zigzagged portions to form meshes of relatively smaller width, and in which interwoven secondary strands are interposed between these smaller meshes.

In the embodiment of Fig. 1, each major strand has its upper and major zigzag formations 1 (or V-shaped parts each of which has a horizontal axis) of the same effective spread or length S as the effective length L of the zigzag parts 2 of the lower and minor zigzag portion of the same major strand. However, the effective width W of the major

zigzag formations 1 is approximately twice that of the width W¹ of each of the minor zigzag formations 2. These minor zigzag formations 2 in each two consecutive major strands are connected by two relatively intertwined secondary strands 3 each of which is formed as the counterpart of the minor zigzagged portion of a major strand, thereby interposing two relatively intertwined secondary strands 3 between the minor portions of two consecutive major strands.

The lower ends of all of the consecutive minor zigzagged wire portions in the fabric of Fig. 1 are intertwined, as also the upper ends of each pair of secondary strands interposed between two major strands. Thus constructed, the resulting wire fabric has meshes of uniform length, but the meshes in the lower portion are of approximately one-half the width of those in the upper portion, so that such a fabric will readily form a unitary and cheaper substitute for the two separate fabrics heretofore employed as (in fences for poultry runways) where the lower part of the fence requires smaller meshes than those which are ample for higher parts of the fence.

In making such a fabric, the wire for each strand is first bent into a flattened spiral formation after the general manner of the strands used for making ordinary chain-link wire fabrics, and the major portions of the consecutive main strands are interlocked with each other by a relative spirally advancing movement of one strand lengthwise of the preceding major strands. This leaves the minor zigzagged portions of each two consecutive main strands freely spaced transversely of the longitudinal axis X of each main strand, or spaced longitudinally of the fabric. Then the secondary strands 3 are interposed between the minor zigzagged portions of the consecutive main strands and interlinked with each other and with adjacent parts of the major strands by spirally advancing movements toward the major zigzagged portions of the main strands in a direction which would be upward in Fig. 1.

Since the minor zigzagged portions of the consecutive main strands have a much narrower spread than the major zigzagged portions of the same strands, the presence of these minor zigzag formations does not interfere with the initial intertwisting (or so-called "interweaving") of these major zigzagged portions of the main strands.

The heights L of the minor zigzag formations are also immaterial, and may be considerably different from the height S of the major zigzag formations in the same main strand, provided that this height L is the same both in the minor zigzag formations of the main strands and in the secondary strands.

Indeed, this height may even be different

for various parts of the minor zigzag portions. For example, in Fig. 2, the alternate major strands A each have uniformly small lower zigzag portions each comprising two legs (or mesh sides) C of about half the length of the legs of each upper zigzag formation 1. Each major strand B which alternates with the strands A has an additional long leg D extending below the lowest of the long legs 1 in the strands A, and one of every two secondary strands has a long upper leg E corresponding in length to the said legs 1 and D. As the result, the fabric of Fig. 2 presents lower meshes of approximately one-fourth the size of its upper meshes.

Fig. 3 shows a fabric formed of two main strands A and B alternating with each other and having counterpart major zigzag portions but slightly different minor portions, together with two slightly differing types C and D of minor strands. Each main strand A has all of its minor zigzag formations 4 corresponding in length and width to all of the minor zigzag formations of the minor strands C, this width being effectively one-third of the width of the major zigzag formations in the strands A. Each secondary strand D has all except the upper leg of its zigzag formations of the same length as those of the secondary strands C, and the portion of each main strand B below the large meshes of the fabric is a counterpart of these secondary strands D.

In the fabric of Fig. 4, the main strands are all counterparts, and the uppermost legs 6 of the minor zigzag formations in consecutive main strands present bights directed toward each other, which bights are connected by two relatively interlinked secondary wires 7. Certain of the other secondary wires have uppermost legs 8 effectively twice the length of the legs in all of the zigzag formations below these uppermost legs.

In the fabrics of Figs. 1 to 4, the upper end of each secondary wire is intertwined with the upper end of another secondary wire, but for many purposes, an intertwisting of only part of the secondary wires at their upper ends will suffice. Thus, Fig. 5 shows a fabric in which adjacent pairs 8 of the secondary wires are intertwined at their upper ends, while the intervening pairs of secondary wires 9 have their upper ends unsecured. Hence I do not wish to be limited as to the securing of the ends of the secondary wires which are adjacent to the larger mesh-forming (or major zigzagged) portions of the fabric.

Nor do I wish to be limited to the relative positions of the large and small meshes in the fabric, as the fabrics of Figs. 1 to 5 could obviously be inverted. Indeed, my invention can also be employed for fabrics

having more than two different sizes of meshes in different portions thereof.

Thus, Fig. 6 shows a fabric in which each main strand has a major zigzag portion 14 interposed between two strand parts 14^A and 14^B of minor formation; the terms "major" and "minor" being here used to designate the relative depth of the zigzag formations transversely of the strand, or longitudinally of the resulting fabric.

In fabricating the fabric of Fig. 6, the consecutive main strands are first spirally twisted through each other to interlock their said major parts 14, while leaving the minor parts 14^A and 14^B of the consecutive strands freely spaced from each other. Then the upper secondary strands 15 (which correspond in their zigzag formations to the upper minor parts 14^A of the major strands) are intertwined with each other and with the said upper parts 14^A of the major strands by a downward spiraling movement of these secondary strands, and the lower secondary strands 16 are similarly connected to each other and to the lower minor parts 14^B of the major strands by an upward spiraling movement of the said lower secondary strands.

However, while I have heretofore described embodiments of my invention in which every main strand extends across the entire width of the fabric, I also do not wish to be limited in this respect, since a strength and rigidity ample for many purposes may be secured without having all of the main strands of the same length. For example, Fig. 7 shows a fragment of a fabric in which the alternate pairs of main strands 11 extend for the entire width of the fabric, while the interposed pair of main strands 12 are shorter and have their lower ends respectively intertwined with the upper ends of certain of the secondary strands 13.

Since suitable flattened spiral or other zigzag formations can be cheaply formed in wires by available machinery, and since the intertwisting or interlinking of such wires with the aid of available machines is also a speedy and inexpensive procedure, chain-link wire fabrics can readily be constructed according to my invention to meet an endless variety of requirements as to the sizes and relative positions of the different meshes.

It also enables me to obtain decidedly ornamental effects while employing spirally intertwined or interengaged zigzagged wires of the cheaply manufactured chain link wire type.

To simplify a designing of such fabrics and the arranging of the tools for making the strands, I desirably dispose both the major and the minor zigzagged portions of each main strand so that their extreme bight edges at one side of the strand are all tangent to a single straight line, such as the line S in Figs. 120

1 and 6. However, I do not wish to be limited in this respect, nor limited to other details of the construction and arrangement here disclosed, since changes may be made ⁵ without departing either from the spirit of my invention or from the appended claims.

I am aware that wire fabrics suitable for fencing poultry yards and the like have heretofore been constructed with upper mesh portions larger than the lower ones, by means of special machines which simultaneously form both sizes of meshes from strands extending longitudinally of a fabric. However, such fabrics require quite expensive machinery ¹⁰ for their manufacture, require the adjacent strands to be twisted several times around each other at each juncture thereof, and also require the interposing of additional straight wires between the large meshed section and ¹⁵ the small-meshed section of the strand. Since wire fences usually are only supported by widely spaced posts, an ordinary chain link (or simple interlinking of merely V-shaped bights) will not suffice when the strands extend horizontally, since the strands would not ²⁰ remain properly interlinked when one fence post tilts out of its initial position toward an adjacent one. Consequently, the adjacent strands have to be adjoined by twists which ²⁵ are only feasible with quite thin or unusually ductile wires. What is more, such fabrics with long intertwists between the adjacent strands cannot readily be rolled up for compact shipment, except when made of too small ³⁰ a size of wire to afford the rigidity desired in many cases.

My present invention overcomes these objections by forming the fabric of strands extending transversely of the fabric or upright ⁴⁰ in an erected fence or grille, thereby permitting the use of simple zigzag or socalled chain-link strands which require no complicated and highly expensive machinery for their manufacture, since they are separately formed before they are assembled. In the resulting fabric, each strand is substantially hinged to the next strand by the interlinking ⁴⁵ of their bights, so that the fabric can readily be rolled up even when made of heavy and stiff wire. Consequently, my invention permits the use of more rigid wires and the manufacture of the fabric with much less expensive machinery.

I claim as my invention:

- 55 1. A chain-link wire fabric formed of interlinked zigzagged strands comprising main strands having the zigzag portions of consecutive strands directly interlinked in a portion of the fabric, certain of the main strands presenting non-contiguous zigzagged portions in consecutive strands in another portion of the fabric; and secondary strands interposed between the said non-contiguous portions of the said main strands.
- 60 2. A chain-link wire fabric as per claim 1,

in which each of the main strands has the bights of all of its zigzagged formations in alignment longitudinally of the strand at one edge of the strand.

3. A chain-link wire fabric formed of interlinked zigzagged strands comprising main strands having the zigzag portions of consecutive strands directly interlocked in a portion of the fabric, certain of the main strands presenting non-contiguous zigzagged portions in consecutive strands in another portion of the fabric; and secondary strands interposed between the said non-contiguous portions of the said main strands, the secondary strands being substantially equal in length to the non-contiguous portions of the said certain main strands.

4. A chain-link wire fabric comprising zigzagged wire strands having parallel axes, the fabric having a large meshed part thereof formed by the directly intertwined widely zigzagged portions of consecutive main strands each of which strands also has another relatively narrower zigzagged portion; the fabric having a smaller meshed part thereof composed of the said narrowed zigzagged portions of the main strands in conjunction with secondary strands corresponding in their zigzagged formation to the said narrower zigzagged portions of the main strands.

5. A chain-link wire fabric affording meshes of two different sizes in different sections extending side by side longitudinally of the fabric, the said fabric comprising intertwined zigzagged wire strands all having their axes transverse of the fabric, including main strands having wide counterpart zigzagged longitudinal portions directly intertwined in consecutive strands to form wide meshes, the main strands also having narrower counterpart zigzagged longitudinal portions, and secondary strands interposed between and interlinked with the said narrower portions of consecutive main strands and with one another to form narrower meshes.

6. A strand for a chain-link wire fabric comprising a flattened spiral presenting major counterpart zigzag formations in one longitudinal portion thereof, and presenting minor counterpart zigzag formations of less width in another longitudinal portion of the strand, the widths of the zigzag formations in each of the said two strand portions being substantially a multiple of a common distance.

7. A strand for a chain-link wire fabric comprising a flattened spiral presenting major counterpart zigzag formations in one longitudinal portion thereof, and presenting minor counterpart zigzag formations of less width in another longitudinal portion of the strand, all of the said zigzag formations in the strand having the bights thereof alining

- longitudinally of the strand at one edge of the strand.
8. A strand for a chain-link wire fabric comprising a flattened spiral presenting major counterpart zigzag formations in one longitudinal portion thereof, and presenting minor counterpart zigzag formations of less width in another longitudinal portion of the strand, the widths of the zigzag formations in each of the said two strand portions being substantially a multiple of a common distance, the widths of the zigzag formations in the major portion of the strand being an exact digital multiple of the width of the zigzag formations in the minor portion of the strand.
9. A strand for a chain-link wire fabric comprising a flattened spiral presenting major counterpart zigzag formations in one longitudinal portion thereof, and presenting minor counterpart zigzag formations of less width in another longitudinal portion of the strand, the widths of the zigzag formations in each of the said two strand portions being substantially a multiple of a common distance, the major zigzag formations having a common longitudinal axis, and the minor zigzag formations having a common longitudinal axis parallel to but laterally offset from the aforesaid axis.
10. A chain-link wire fabric composed of spirally intertwined main strands each of which main strands has a zigzag portion directly interlinked with a similarly formed zigzag portion in the next consecutive main strands, the consecutive main strands also presenting non-contiguous portions of counterpart narrower zigzag formations than those of their aforesaid portions, and a relatively larger number of secondary strands corresponding substantially in length and in zigzag formations to the non-contiguous portions of the main strands, the said secondary strands and the said non-contiguous portions of the main strands being relatively interlinked to form a fabric portion having smaller meshes than those formed by the direct interlinking of the first-named zigzag portions of the main strands.
11. A chain-link wire fabric comprising main strands extending for the entire width thereof, the consecutive main strands having counterpart widely zigzagged portions directly interlinked to form large meshes, the said main strands also having secondary counterpart zigzag portions of narrower formation disposed in another part of the said strands and non-contiguous in the consecutive strands, and secondary strands corresponding in length and formation to the secondary zigzag portions of the main strands, a plurality of the secondary strands cooperating with the said zigzag portions of the main strands to form a chain-wire link fabric part of smaller mesh than the said large meshes.
12. A chain-link wire fabric comprising main strands having wide counterpart portions of wide zigzag formation and secondary counterpart portions of narrower zigzag formation, the consecutive main strands having their said wide portions interlinked and each having its secondary portion spaced from the secondary portion of an adjacent strand; and minor strands each having zigzag formations corresponding to the secondary counterpart portions of the main strands, the minor strands being interlinked with each other and with the said spaced secondary portions of the main strands.
13. A chain-link wire fabric comprising counterpart main strands each having a wide portion of wide zigzag formation and a secondary portion of narrow zigzag formation; the wide portions of consecutive strands having their bights interlinked; and minor strands interposed between secondary portions of consecutive main strands, the said minor strands and secondary portions of main strands being interlinked in the usual chain-link manner to form a fabric section with narrower meshes than those formed by the wide portions of the main strands.
14. A chain-link fabric comprising counterpart main strands each having a wide portion of wide zigzag formation and a secondary portion of narrower zigzag formation, the width of the wide zigzag formations being a multiple of the width of the narrower zigzag formations; and the portions of consecutive strands having bights interlinked; and minor strands counterpart to and interposed between secondary portions of the main strands, the said minor strands and secondary portions being consecutively interlinked to form narrower meshes than those formed by the wide portions of the main strands.
15. A chain-link wire fabric composed of preformed and spirally intertwined zigzagged strands; comprising main strands having the zigzag portions of consecutive strands directly interlinked in a portion of the fabric, certain of the main strands presenting non-contiguous zigzagged portions in consecutive strands in another portion of the fabric; and interlinked secondary strands interposed between the said non-contiguous portions of the said main strands and directly interlinked with the said non-contiguous portions being consecutively interlocked to
16. A chain-link wire fabric composed of preformed and spirally intertwined zigzagged strands; comprising main strands having the zigzag portions of consecutive strands directly intertwined in a portion of the fabric, certain of the main strands presenting non-contiguous zigzagged portions in consecutive strands in another portion of the

fabric; and secondary strands interposed between the said non-contiguous portions of the said main strands, the secondary strands being intertwined with each other and with the said non-contiguous portions of the main strands, the secondary strands being substantially equal in length to the non-contiguous portions of the said certain main strands.

17. A chain-link wire fabric composed of spiral strands flattened to a zigzag formation presenting simple U-shaped bights at each edge of each strand; comprising main strands extending for the entire width of the fabric, the consecutive main strands having counter-
part widely zigzagged portions disposed with the bights in adjacent strands directly intertwined to form large meshes, the said main strands also having secondary counterpart zigzag portions of narrower formation disposed in another part of the said strands and non-contiguous in consecutive strands; and a plurality of secondary strands corresponding in length and formation to the secondary zigzag portions of the main strands, some of the secondary strands having the bights at one edge thereof interlinked with the bights of the secondary portions of main strands, and other secondary strands being intertwined with two of the last-named secondary strands, so that the secondary strands cooperate with the secondary portions of the main strands in forming a chain-wire link fabric portion of smaller mesh than the aforesaid larger meshes.
